JAMES E. CHEESMAN, OF SOUTH ORANGE, NEW JERSEY, ASSIGNOR TO EMPIRE DUPLEX GIN COMPANY, OF NEW YORK, N. Y., A CORPORATION OF ARIZONA.

PROCESS OF TREATING LINT.

1,128,758.

Specification of Letters Patent.

Patented Feb. 16, 1915.

Application filed May 10, 1911. Serial No. 626,222.

To all whom it may concern:

Be it known that I, JAMES E. CHEESMAN, a citizen of the United States of America, and a resident of South Orange, county 5 of Essex, and State of New Jersey, have invented certain new and useful Improvements in Processes of Treating Lint, of which the following is a specification, reference being had to the accompanying 10 drawings, forming a part thereof.

My invention relates to a novel method of treating lint to clean and separate the fibers. Cotton lint, particularly as it is received from a roller cotton gin, is in a somewhat 15 matted condition and carries with it a certain percentage of dirt, dust, leafy trash, etc.

The object of the present invention is to improve the condition of the lint by opening 20 out and separating the fibers, and cleaning them, to the end that the final product may be in a clean, homogeneous, and fluffy condition.

In a copending application, serially numbered 25 604,320, filed January 24, 1911, I have disclosed and claimed a process in which the lint is moved by air currents past a plurality of fingers which project obliquely in the direction of the flow of the currents, 30 whereby the lint is arrested from time to time by the fingers while the air is acting upon the same, and by which the fibers are opened out and changed from their matted to a more fluffy condition, and in being so 35 opened out are cleaned in the sense that dirt, dust, leafy trash, etc., is removed therefrom.

My present invention relates to such a process, and consists essentially in varying 40 the velocity of the air currents while the lint is being treated so that while the lint when in its matted condition is thrown with considerable force against the fingers, the force with which it is so thrown is gradually decreased as the fibers are opened out. By 45 this means a maximum of efficiency is obtained, for it will be well understood that while a greater force should be employed while the fibers are closely matted, a less 50 force is desirable after the fibers have been opened out. Any suitable form of appa-

ratus may be employed for carrying out such process, and I refer to a copending application serially numbered 626,221, filed upon even date herewith for one such form 55 of apparatus.

The drawing herewith represents in somewhat diagrammatic form such an apparatus, in which a lint flue 5 contains a channel 6 formed in a plurality of horizontal 60 superposed sections whose cross-sectional area progressively increases from the section which first receives the material to be treated, to the section from which it is finally discharged. A blower 7 draws lint 65 from a gin 8 or other source of supply, and delivers it to the channel 6. As the cross-sectional area of the channel 6 increases from one end to the other it follows that the speed of the air currents therethrough will 70 decrease in proportion thereto. The channel 6 is provided with fingers 9 throughout the length thereof, against which the lint will be thrown, and by which the lint will be temporarily arrested from time to time in 75 its travel through the flue. As the velocity of the air currents decreases in the travel of the air through the channel, it follows that the severity of the action of the fingers upon the lint will relatively decrease as the lint 80 passes from one end of the channel to the other.

What I claim is:

1. The herein described process of treating lint which consists in moving it by air 85 currents arranged to flow in a zigzag path, temporarily retarding the advance and oppositely changing the direction of movement of particles of said lint relative to said currents at fixed intervals along its path of 90 travel, whereby the air currents are caused to blow through said lint, subjecting said particles of lint to a combing action at the end of said fixed intervals of retarded advance and cleaning the lint at the turns in 95 said zigzag air current path.

2. The herein described process of treating lint which consists in moving it by air currents arranged to flow in a zigzag path, temporarily retarding the advance and oppositely changing the direction of movement of particles of said lint relative to said cur- 100

rents at fixed intervals along its path of travel, whereby the air currents are caused to blow through said lint, subjecting said particles of lint to a combing action at the end of said fixed intervals of retarded advance, cleaning the line at the turns in said zigzag air current path and in progressively

reducing the velocity of the air currents in the advance thereof.

JAMES E. CHEESMAN.
